UNITED STATES PATENT OFFICE.

RYUJI SATO, OF NEW YORK, N. Y.

WINDOW SHADE.

Application filed January 6, 1922. Serial No. 527,403.

To all whom it may concern:

Be it known that I, Ryuji Sato, a citizen of Japan, residing at New York city, in the county of New York and State of New York, have invented new and useful Improvements 5 in Window Shades, of which the following is a specification.

This invention relates to window shades, and the principal object is to produce a 10 device of this nature which may be utilized to cut off the light from a window by moving the obstruction down or up in front of the window aperture.

Another object is to produce a device of 15 this nature which shall be simple of construction, cheap to manufacture, and highly efficient for the purpose for which it is designed.

Another object is to produce a device of 20 this nature having special reinforcement for preventing stretching and distortion at the points of greater strain.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a view of a window frame provided with my improvement and arranged to obstruct a portion of the light from the top of the window.

Figure 2 is a similar view with the obstruction at the bottom.

Figure 3 is a longitudinal section of one of the curtain rods.

Figure 4 is an extended view of the curtain.

Figure 5 is an enlarged detail vertical sectional view on the line 5—5 of Figure 1.

Like characters of reference refer to like parts in all views.

Referring to the drawing in detail, it will be noted that the curtain proper which is indicated at 10 is three times the length of the ordinary window curtain necessary for the desired length of window aperture.

The third of the curtain at each end is solid as is the ordinary curtain and the central third is apertured as at 11 forming side strips 12, the material from the aperture 11

being folded back so as to finish and reinforce the edges of the aperture. At the top and bottom of the aperture 11 springy strips

13 preferably of thin sheet steel are sewed into the structure so as to prevent the crushing together of the curtain and to cause it to roll improperly at each end. The window frame is shown at 14 having the usual aperture 15 to register with the aperture 11 in the curtain.

The brackets are shown at 16 and are preferably formed of spring steel which tend 65 constantly to press toward the center. As two rollers are used in the present construction, two pairs of brackets are shown arranged above and below the aperture 15, respectively. The roller proper is numbered 17 and is provided with the usual bracket engaging studs 18. Mounted loosely on a reduced portion at one end of the roller is a pulley member 19 having ratchet teeth 20 formed on its inner face and adapted to engage with ratchet teeth 21 on the adjacent portion of the roller 17. The teeth are so set that when the pulley is turned to wind the curtain on the respective roller, the teeth on the pulley of the other roller will ratchet 70 idly so as to permit of the necessary advance in movement due to the difference in size of the rolls as the curtain is wound from one to another. A cord or belt 22 connects the two pulleys so that by turning the belt in one direction one pulley will be caused to roll the curtain upwardly while in turning the belt in the opposite direction, the other pulley will be caused to roll the curtain in 75 the opposite direction.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A device of the class described comprising a pair of curtain rollers one adapted to be arranged in spaced relation to the other upon a window frame, a curtain equal to three times the length of the window frame having its opposite ends secured to said rollers, and an aperture in said curtain equal to the length of the window opening in said frame.

2. A device of the class described comprising a pair of curtain rollers one adapted to be arranged in spaced relation to the other

- upon a window frame, a curtain equal to three times the length of the window frame having its opposite ends secured to said rollers, and an aperture formed centrally of said curtain equal to the length of the window opening in said frame, and means when said aperture is in registration with the window for moving said curtain in either direction for obstruction light through the window.
- 10 3. A device of the class described comprising a pair of curtain rollers, a curtain equal to three times the length of a window equal on which the same is to be used and having an opening formed centrally therein equal to one-third its length and having its ends secured to said rollers, a manipulating means connecting said rollers and common to both for moving said curtain in opposite directions.
- 15 4. A device of the class described comprising a pair of curtain rollers, a curtain equal to three times the length of a window frame on which the same is to be used and having an opening therein equal to one-third its length and having its ends secured to said rollers, strips of springy material inserted in said curtain at opposite ends of said opening, a manipulating means connecting said rollers and common to both for
- 20 30 moving said curtain in opposite directions.

5. A device of the class described comprising a pair of rollers, a curtain provided with an aperture and having its ends secured to said rollers, strips of springy material inserted in said curtain at opposite ends of said aperture, ratchet teeth formed on one end of each of said rollers, pulleys mounted adjacent said rollers and having ratchet teeth for co-action with the teeth on said rollers respectively, the ratchet teeth of one roller and its mating pulley being opposite those of the other roller and pulley, and a belt connecting said pulleys for effecting movement of said curtain in either direction.

35 6. In a device of the class described, the combination with a window, a pair of rollers, one of said rollers arranged at the top of said window and the other at the bottom thereof, a curtain equal to three times the length of said window, provided centrally thereof with an aperture and equal to one-third the length of said curtain, and means for moving said curtain in opposite directions for bringing said aperture into and out registration with said window whereby the amount of light through said window may be regulated.

In testimony whereof I have affixed my signature.

RYUJI SATO.
